US00D786897S

(12) **United States Design Patent** (10) **Patent No.:** **US D786,897 S**
Nageli et al. (45) **Date of Patent:** **** May 16, 2017**

(54) **DISPLAY SCREEN OR PORTION THEREOF WITH GRAPHICAL USER INTERFACE**

(71) Applicant: **Harman International Industries, Incorporated**, Northridge, CA (US)

(72) Inventors: **Shawn Nageli**, South Jordan, UT (US); **Iain Gregory**, Cleveland, OH (US)

(73) Assignee: **Harman International Industries, Incorporated**, Northridge, CA (US)

(**) Term: **15 Years**

(21) Appl. No.: **29/569,106**

(22) Filed: **Jun. 23, 2016**

Related U.S. Application Data

(63) Continuation-in-part of application No. 29/493,865, filed on Jun. 13, 2014.

(51) **LOC (10) Cl.** **14-04**

(57) **CLAIM**

The ornamental design for a display screen or portion thereof with graphical user interface, as shown and described.

DESCRIPTION

The FIGURE is a front elevational view of a display screen or portion thereof with graphical user interface showing our new design.

The outermost broken lines in the FIGURES show a display screen or portion thereof, and form no part of the claimed design. The broken line showings of the other indicia, elements and remainder of the display screen form no part of the claimed design.

1 Claim, 1 Drawing Sheet
